(57) **CLAIM**

The ornamental design for a dispenser for liquid soap, as shown and described.

DESCRIPTION

FIG. 1 is a perspective view of a dispenser for liquid soap showing our new design;

FIG. 2 is a front elevation view thereof;

FIG. 3 is a side elevation view thereof;

FIG. 4 is a rear elevation view thereof;

FIG. 5 is a top view thereof;

FIG. 6 is another perspective view of the embodiment of FIG. 1 showing the spout in a second orientation;

FIG. 7 is a front elevation view showing the spout in the orientation of FIG. 6;

FIG. 8 is a perspective view of a second embodiment of our new design;

FIG. 9 is a front elevation view thereof;

FIG. 10 is a side elevation view thereof;

FIG. 11 is a top view thereof;

FIG. 12 is another perspective view of the embodiment of FIG. 8 showing the spout in a second orientation; and, FIG. 13 is a front elevation view showing the spout in the orientation of FIG. 12.

The subject matter shown in broken lines is for illustrative purposes only and forms no part of the claimed design. The bottom views (not shown) form no part of the claimed design.
